A. L. SWAN, OF CHERRY VALLEY, NEW YORK.

Letters Patent No. 88,925, dated April 13, 1869

IMPROVEMENT IN VALVES AND VALVE-SPRINGS FOR MELODEONS, &c.

The Schedule referred to in these Letters Patent and making part of the same

To all whom it may concern:

Be it known that I, A. L. SWAN, of Cherry Valley, in the county of Otsego, and State of New York, have invented a new and useful Improvement in Valves and Valve-Springs for Melodeons, Organs, &c.; and I do hereby declare that the following is a full, clear, and exact description thereof, which will enable others skilled in the art to make and use the same, reference being had to the accompanying drawings, forming part of this specification.

This invention relates to improvements in valves and the springs employed for closing them, such as are used in melodeons, organs, and other similar instruments, designed to produce valves which will close more tightly, and more durable and sensitive springs.

Figure 1 represents a longitudinal section of a valve and spring arranged according to my improvements, and

Figure 2 represents a similar view of the present arrangement of the same.

Similar letters of reference indicate corresponding parts.

A represents the valve, which, according to the present arrangement, is packed with a piece of cloth, or felt, *a*, and leather, *b*.

As the leather must necessarily be very thin and soft, it cannot be impervious to air, and consequently when so packed, the valves leak considerably. Rubber and oiled silk have been substituted for the leather, but these being of a gummy nature, adhere to the wood surface of the valve-seat, and render the action of the valves, unreliable.

To obviate these difficulties, I interpose a thin layer of India rubber, or oiled silk, *c*, between the cloth and the leather, making the latter extremely thin, having only sufficient substance to prevent the adherence of the silk or rubber.

By this plan I have a soft and noiseless cushion of cloth, an intermediate sheet of substance impervious to air, and a surface that will not adhere to the valve-seat, which I have found, in practice, to prevent the escape of air in a great degree, and saving materially in the labor of working the bellows.

B represents the springs, as commonly arranged, for

closing the valves, being bent at right angles at D, and fastened to the block E, by being driven into holes therein, the other ends bearing and sliding on the backs of the valves, as represented at F.

By this arrangement only the elasticity of that portion of the spring which forms the bend at D is available, the balance of it acting as a lever upon this most yielding part; they are therefore not as sensitive as desirable, and soon fail; moreover, considerable friction exists at the point F, and they cannot well be taken out, as is often required.

The combined strain of the great numbers of these springs employed in an organ acting upon the block E, by which they are supported, often causes it to yield, and become misplaced, and, finally, this plan of arrangement necessitates the employment of a guiding pin, *d*, for one end of the valve.

According to my improved plan of arrangement, the spring G is made longer, and provided with a coil at H, taking into a corresponding recess in the back of the valve, the rear end passes through a tapered longitudinal slot, I, in the valve, by which the valve is supported laterally, and the spring hooks on to a pin, K, traversing a slot in the supporting-bar L, made for the reception of the said spring; the other end hooks into a leather, or other yielding support, M.

By this arrangement, the spring is made readily detachable; to remove the valves, the friction at the point F is avoided, by the action of the yielding support M, and a much more durable and elastic spring is provided, as will be readily understood.

Having thus described my invention,

I claim as new, and desire to secure by Letters Patent—

1. Packing the valves for organs, melodeons, &c., with the cloth strips *a*, India rubber, oiled silk, or other substance, *c*, impervious to air, and the thin leather layer *b*, all arranged as specified.

2. The springs G, constructed and combined with the valves, substantially as specified.

A. L. SWAN.
